UNITED STATES PATENT OFFICE.

THOMAS JAMES AVERY, OF ALBIA, IOWA.

COMBINATION SCRAPER, CHARGER, AND TAMPER.

1,379,435.

Specification of Letters Patent. Patented May 24, 1921.

Application filed August 4, 1920. Serial No. 401,260.

To all whom it may concern:

Be it known that I, THOMAS J. AVERY, a citizen of the United States, and a resident of Albia, in the county of Monroe and State 5 of Iowa, have invented a new and useful Improvement in Combination Scrapers, Chargers, and Tampers, of which the following is a full, clear, and exact description.

My invention relates to improvements in 10 combination scrapers, chargers, and tampers, and it consists in the combinations, constructions, and arrangements herein described and claimed:

An object of my invention is to provide 15 a combination scraper, charger, and tamper for use in blasting operations, such as in mining coal, or the like, which combines in one tool means for effectively performing a plurality of functions ordinarily per-

20 formed by a number of separate tools.

A further object of my invention is to provide a device of the type described that can be used in placing and tamping an explosive charge in a desired position for firing without any possibility of producing a spark, whereby the danger of causing a premature explosion is obviated.

A further object of my invention is to provide a device of the type described that 30 has means for holding an explosive charge until moved into a desired position and for ejecting the charge in such position, whereby the charge is not scattered along a hole drilled for the reception thereof, as ordinarily occurs.

A further object of my invention is to provide a device of the type described that is relatively simple in construction and thoroughly practical commercially.

40 Other objects and advantages will appear in the following specification, and the novel features of the invention will be particularly pointed out in the appended claims.

My invention is illustrated in the accompanying drawings, forming part of this application, in which—

Figure 1 is a plan view of the device,

Fig. 2 is a longitudinal section, partly in elevation, of the device,

50 Fig. 3 is an end view of a portion of the device,

Fig. 4 is a plan view of the portion of the device shown in Fig. 3.

In carrying out my invention, I provide 55 a cylindrical barrel 1 formed with an out-

wardly extending flange 2 at its rearward end, which engages with a ring 3 and maintains the latter in position on the rearward end of the barrel. The ring 3 is formed with rearwardly extending arms 4-4, which are 60 bent inwardly toward each other and are hinged at 5 to a coupling 6. The coupling 6 in the form now preferred by me is special in construction, and will be hereinafter described in detail.

Screwed into a threaded bore 8 in the coupling 6 is the threaded end of a sleeve 7. The other end of the sleeve 7 is threaded and is screwed into the forward end of a coupling 9. The coupling 9 is fashioned 70 with diametrically opposed longitudinal slots 10 and 11 which extend circumferentially in the same direction at 12 and 13 respectively.

A rod 14 is slidable within the sleeve 7 75 and is sufficient in length to have one end projecting a predetermined distance within the barrel 1 when its other end is substantially received within the coupling 9. A scraper comprising a stem 15 and a scraping 80 member 16, which is carried at right angles to the stem 15, is secured to the rearward end of the rod 14. This is accomplished by screwing the stem 15, which is formed with a threaded bore for that purpose, on the 85 threaded end of the rod 14 until the diametrically opposed openings 17 through the stem 15 register with an opening (not shown) which extends through the rod 14 adjacent its end. A pin 19 is then inserted 90 through the registering openings to maintain the tamper in its position. The edges of the openings 17 are beveled; wherefor the end of the pin 19 is countersunk to permit 95 slidable movement of the end of the stem 15 within the coupling 9.

The slidable movement of the stem 15 within the coupling 9 is limited by the oppositely disposed studs 20-20 which enter the slots 10 and 11. The stem 15 is locked 100 in position when the studs 20-20 are maintained in the circumferentially extending slots 12 and 13 by the action of a spring pressed stud 21 which engages with the walls of one of the slots 10 or 11.

It will thus be obvious that scrapers having stems varying in length may be used and that the relative position of the scraping member of each scraper will be the same.

The forward end of the rod 14 is flat- 110

tened at 21' and is received within a slot 22 in the stem 23 of a plunger 24, which is slidable within the cylindrical barrel 1. A pin 25, or the like, hingedly connects the 5 end of the rod 14 and the plunger stem 23.

The coupling 6 has its sides flattened exteriorly at 26-26 (see Figs. 3 and 4) to engage with the arms 4-4. The top side of the coupling 6 is cut away to provide a 10 socket 27 having its parallel straight side walls recessed at 28-28. The upset inner ends of the rivets or pins effecting the hinged connection of the arms 4-4 and the coupling 6 are disposed within the recess 15 28-28. The arms 4-4 are provided with registering openings 29-29, which register with openings 30-30 through the side walls of the coupling 6 and an opening 31 through the shank of the plunger 24 when the barrel 20 1 is in the position pictured in Fig. 4 of the drawings for a purpose that will be hereinafter set forth.

From the foregoing description of the various parts of the device, the operation 25 thereof may be readily understood. When the device is in the condition pictured in Fig. 1 of the drawings, it may be used as a tamper, since the head of the plunger 24 projects beyond the forward end of the cylindrical barrel 1. It will of course be understood that the cylindrical barrel 1, the plunger 24, and the sleeve 7 are all formed of some suitable material, preferably brass, which is non-ferrous so that the danger of 30 causing a spark by contact of the same with the work is thereby obviated. When it is desired to use the device as a scraper, the studs 20 are turned in position to be moved along the slots 10 and 11. The tamper is 35 then moved into extended position, thereby moving the stem of the plunger 24 into the position indicated by the dotted lines in Fig. 2. A cotter pin or the like is then inserted through the registering openings 29, 30, 40 and 31, thereby preventing retraction of the scraper. It will be understood that the scraper is used in removing the drillings and the like from the hole, which has been drilled in the coal or other material that is 45 to be blasted. When the plunger 24 is in the position pictured in Fig. 2, the cylindrical barrel 1 may be swung upwardly into the position illustrated by the full lines in Fig. 2 when the cotter pin has been with- 50 drawn from the registering openings 29, 30, and 31. This cannot be accomplished, however, until the stem 23 of the plunger 24 occupies the position shown by the dotted lines in Fig. 2. It will then be observed 55 that the head of the plunger forms a closure for the cylindrical barrel 1. A suitable charge of powder or the like may be placed within the cylindrical barrel 1 and the forward end of the device inserted within the 60 drilled hole in the coal until the position 65

at which the charge is to be placed is reached. The charge is then ejected by pushing the rod 14 forwardly. The device is then in the condition pictured in Fig. 1 of the drawings and may be used to tamp 70 the charge.

The device provides means for effectively accomplishing a number of related objects with a saving in time and labor. Since no ferrous material is exposed or may be 75 brought into contact with the material to be blasted or other material that may cause a spark, the danger of a premature explosion is reduced to a minimum when my improved device is used.

It will be observed that the stem or shank 23 of the plunger is formed with parallel sides arranged to slidably contact with the sides of the socket 27 when the plunger is 80 in retracted position to prevent rotation of 85 the barrel 1.

I claim:

1. A device of the character described comprising a cylindrical non-ferrous barrel, a non-ferrous plunger slidable in said barrel and provided with a rearwardly extending shank, a non-ferrous sleeve, a non-ferrous coupling carried at the forward end of said sleeve, a rod extending through said sleeve and having its forward end hinged to the end of the plunger shank, means for hingedly connecting the rearward end of said cylinder to said coupling to permit said cylinder to be swung upwardly into a position at right angles to said coupling when 100 said plunger is in its retracted position, a tamping member having a stem removably secured to the rearward end of said rod, a stud projecting from the last named stem at a spaced distance from the end thereof, a 105 coupling carried on the rearward end of said sleeve, said coupling being formed with a slot through the wall thereof adapted to receive said stud when the rod is moved forwardly through the sleeve, said slot being 110 extended longitudinally a spaced distance and then circumferentially wherefor the plunger may be moved forwardly through the cylindrical barrel until the forward end thereof projects beyond the end of the latter, and spring means carried by the stem of 115 said tamping member for engaging with the walls of the slot to normally maintain the stud in the circumferentially extending portion thereof.

2. A device of the character described comprising a cylindrical non-ferrous barrel, a non-ferrous plunger slidable in said barrel and provided with a rearwardly extending shank having parallel straight side walls, a non-ferrous sleeve, a non-ferrous coupling carried at the forward end of said sleeve, said coupling being formed with a socket having straight parallel side walls 125 adapted to coöperate with the straight sided 130

shank of said plunger to prevent rotation of the plunger when the latter is in retracted position, a rod extending through said sleeve and having its forward end hinged to the 5 end of the plunger shank, and means for hingedly connecting the rearward end of said cylinder to said coupling to permit said cylinder to be swung upwardly into a position at right angles to said coupling when 10 said plunger is in its retracted position.

3. In a device of the character described, a sleeve, a coupling having its rearward end secured to said sleeve, said coupling having its side walls flattened exteriorly and in- 15 teriorly at diametrically opposite points and being formed with a longitudinally extending slot through its wall intermediate the flattened portions, a cylindrical barrel having opposed arms at one end thereof, said 20 arms having their outer end portions formed with parallel straight walls pivoted to the exteriorly flattened portions of the wall of said coupling, a plunger slideable in said barrel, said plunger being provided with a rearwardly ex- 25 tending shank formed with straight side walls adapted to closely engage with the interiorly flattened portions of the wall of said coupling, and a rod movable longitudinally in said sleeve, said rod being arranged 30 to have its inner end projecting within said coupling and pivoted to the shank of said plunger, wherefor said plunger and said barrel can be swung upwardly simultane- 35 40 45 50 55 60

simultaneously when said plunger is in its retracted position.

4. In a device of the character described, a sleeve, a coupling having its rearward end secured to said sleeve, said coupling having its side walls flattened exteriorly and interiorly at diametrically opposite points and being formed with a longitudinally ex- 35 tends slot through its wall intermediate the flattened portions, said slot having a width equal to the distance between the interiorly flattened walls of the coupling, a cylindrical barrel having opposed arms at one end thereof, said arms having their outer end portions formed with parallel straight walls pivoted to the exteriorly flattened portions of the wall of said coupling, a plunger slideable in said barrel, said plunger being provided with a rearwardly ex- 40 tending shank formed with straight side walls adapted to closely engage with the interiorly flattened portions of the wall of said coupling, and a rod movable longitudinally in said sleeve, said rod being arranged 45 to have its inner end projecting within said coupling and pivoted to the shank of said plunger, wherefor said plunger and said barrel can be swung upwardly simultane- 50 55 60

THOMAS JAMES AVERY.
